TOILET BOWL DEODORANT HOLDER

Morton A. Rosenheim, Plandome, N.Y., assignor to Ramo Realty Corp., Plandome, N.Y., a corporation of New York

Filed Dec. 18, 1967, Ser. No. 9,823

Term of patent 14 years

(Cl. D23—150)

FIG. 1

FIG. 4

FIG. 2

FIGURE 1 is a front perspective view of a toilet bowl deodorant holder, showing my new design;

I claim:

The ornamental design for a toilet bowl deodorant holder, as shown.
